C. W. Simpson.

Book-Holder

No. 92,482. Patented July 13, 1869.

Fig. 1.

184. PRACTICAL ARITHMETIC
DENOMINATE FRACTIONS

Ex.-3. Add 675 lb., $\frac{2}{3}$ and $\frac{4}{3}$.

$$\begin{array}{r} \text{out gr lb} \\ \hline 825 T = 16 & .675 lb \\ 62 \text{ cwt} = & 2 & 12 \\ & 13 & \hline 10.5003 \\ \text{Ans.} & 15 & 3 & 13 & .7 \end{array}$$

17. From $\frac{2}{3}$ oz. take $\frac{3}{8}$ pwt.

18. From 22 ch. take 43 l.

19. Add $\frac{2}{3}$ yd. $\frac{1}{6}$ ds., $\frac{1}{3}$ h.

20. From $\frac{1}{4}$ hhd take $\frac{2}{3}$ qt.

21. From 375 da take 2 min.

22. From $\frac{5}{7}$ A. take $\frac{1}{4}$ of 3 rods.

23. Add $\frac{1}{2}$ cwt. 3 qr and 4 lb.

24. Add 16 bu. $\frac{1}{6}$ pk. and $\frac{1}{2}$ qt.

25. From 32 lb take 9 $\frac{1}{3}$.

26. From $\frac{1}{2}$ cwt. take $\frac{1}{3}$ x $\frac{1}{2}$ h.

27. How many cu in. in 1 bu. 3 pk. 2.

Ans. 11 $\frac{2}{3}$ 2 $\frac{1}{3}$.

4. From 825 T subtract 62 cwt.

5. Add $\frac{3}{8}$, $\frac{9}{16}$ s. and $\frac{1}{4}$ d.

Inventor:
Carello W. Simpson

United States Patent Office.

CORELLI W. SIMPSON, OF BANGOR, MAINE.

Letters Patent No. 92,482, dated July 13, 1869.

IMPROVEMENT IN BOOK-HOLDERS.

The Schedule referred to in these Letters Patent and making part of the same.

To all whom it may concern:

Be it known that I, CORELLI W. SIMPSON, of Bangor, in the county of Penobscot, and State of Maine, have invented a new and useful or improved Book-Holder; and I do hereby declare that the following, taken in connection with the drawings which accompany and form part of this specification, is a description of my invention sufficient to enable those skilled in the art to which it appertains, to practise it.

This invention relates to a new and useful improvement in holders to retain books open at any desired page, and is especially useful to school-children, preventing their soiling and wearing their books while studying the same.

The invention consists in a curved rigid bar, of nearly the same length as the width of the open book, to each end of which is attached a spring-clasp, formed to embrace one of the lids of the book, while to the centre of the rod is pivoted a suitable spring-holder, which retains the book open at any desired page.

Figure 1 is a perspective view of my invention attached to a book, shown by dotted lines; and

Figure 2 is a vertical longitudinal section, taken through the centre, and showing the joining of the spring-holder to the rigid bar.

Similar letters of reference indicate corresponding parts in the several figures.

In the drawings—

A represents a rigid bar, of a length nearly equal to the width of the open book. The centre of this bar has an upward curve shown at a, and corresponding to the usual thickness of books.

A raised knuckle, d, is formed upon this central part of the rod, and the lever b is pivoted in a transverse slot in the knuckle, as is plainly shown in fig. 2; e being the pivot, connecting the two parts together.

c is both a spring and thumb-piece, for actuating the lever b; this spring being secured to the lever by rivets, as shown in fig. 1.

f represents a knife, and g a fork, secured to the lever b, which terminates in a handle, as shown.

In use, the spring-clasps B B are attached to the respective lids of the book, when, by pressing upon the thumb-piece or spring c, the lever b is raised, and as the spring passes the corner of the knuckle d, it springs the lever to a vertical position, where it remains, and when desired it can be closed by a reverse movement, bringing the holders f g upon the leaves, thus holding the book open until it is desired to turn to another place, when the lever is raised and the pages turned to the desired place.

Having thus described my invention,

What I claim as new, and desire to secure by Letters Patent, is—

A book-holder, constructed with bar A, spring-clasps B B, with the holding-device as constructed, with the lever b, spring c, and arms f g, and arranged to operate substantially in manner as and for the purposes specified.

CORELLI W. SIMPSON.
